AUTOMATIC SOLUTION OF LINEAR SIMULTANEOUS EQUATIONS

George W. Brown, Ames, Iowa, assignor to Radio Corporation of America, a corporation of Delaware

Application November 15, 1946, Serial No. 709,920

14 Claims. (Cl. 235—61)

1

This invention relates to a method of and means for electronically solving linear simultaneous equations.

In a copending application of G. W. Brown and E. A. Goldberg, Serial No. 690,865, filed August 16, 1946, for "Electronic equation solver," there is described a method of and means for electronically solving non-singular linear simultaneous equations whose characteristic roots, while complex, have positive real parts. The primary object of this invention is to overcome this limitation of the earlier system and to ensure the stable solution of non-singular linear equations by electronic feedback methods independently of the nature of the equation and without dependence for stability on the particular equation to be solved. Otherwise stated, the present invention provides universal stability in a feedback type of electronic simultaneous equation solver for all systems of non-singular equations without limitation as to the nature of the characteristic roots. A non-singular set of equations is defined as a set of equations for which a unique mathematical solution exists. Any singular set of equations is one which has at least one vanishing characteristic root.

A general system of n simultaneous equations and n unknown terms may be written

$$Y_1 = a_{11}X_1 + a_{12}X_2 + \dots + a_{1n}X_n \quad (1)$$

$$Y_2 = a_{21}X_1 + a_{22}X_2 + \dots + a_{2n}X_n \quad (2)$$

$$Y_n = a_{n1}X_1 + a_{n2}X_2 + \dots + a_{nn}X_n \quad (n)$$

where $X_1, X_2, \dots, X_n$ are the unknown terms implicitly determined by the n equations;

$Y_1, Y_2, \dots, Y_n$ are the constant terms of the n equations;

$a_{11}, a_{21}, \dots, a_{n1}$ are the coefficients of X_1 in the first, second to n th equations, respectively;

$a_{12}, a_{22} \dots a_{n2}$ are the coefficients of X_2 in the first, second, to the n th equations, respectively; and

$a_{11}, a_{21}, \dots, a_{nn}$ are the coefficients of X_n in the first, second, to n th equations, respectively.

It should be noted that in the terminology herein employed the first subscript of each coefficient "a" identifies the equation in which it is found while the second subscript identifies the particular unknown term X which it modifies.

The simultaneous equations above may be expressed in an equivalent well known matrix form

$$\begin{pmatrix} Y_1 \\ Y_2 \\ \vdots \\ Y_n \end{pmatrix} = \begin{pmatrix} a_{11} & a_{12} & \dots & a_{1n} \\ a_{21} & a_{22} & \dots & a_{2n} \\ \vdots & \vdots & \ddots & \vdots \\ a_{n1} & a_{n2} & \dots & a_{nn} \end{pmatrix} \begin{pmatrix} X_1 \\ X_2 \\ \vdots \\ X_n \end{pmatrix} \quad (4)$$

which says that when the vector whose components are $x_1, x_2 \dots x_n$ is operated on by the matrix of coefficients "a" the result is a new vector whose n components are expressed in Equations 5 (1), (2) . . . (n) above. A further simplification is to let the notation

$$Y = AX \quad (5)$$

10 express the most general form of the matrix equation. In this form A is understood to represent a double series of coefficients "a" to be applied to the series of unknown terms X in a group of equations in which Y represents the set of constant terms.

15 When a vector is operated on by a "transposed" matrix the coefficients "a" are interchanged in rows and columns. This operation is indicated by the term A^T . When a vector is operated on by a matrix A, and the result is operated on by another matrix B, there is an equivalent matrix, denoted by BA , which represents the composite operation.

25 There is a mathematical theorem, which need not be proved herein, that a matrix of the form $A^{tr}A$, corresponding to the step of operating on a vector by A and then operating on the resultant by A^{tr} , has the property that all its roots are always real and positive. That is, $A^{tr}A$ is always positive definite. Thus, if equations $AX=Y$ are 30 replaced by the set

$$A^{tr}A^X = A^{tr}Y \quad (6)$$

having the same solutions as the original set, the characteristic roots of the new system are all positive.

Since the equation solver disclosed in the original disclosure was limited to the solution of linear simultaneous equations whose characteristic roots, while complex, had positive real parts, it follows

40 that a system which expresses the original equations in an equivalent form involving the transposed matrix operation, having positive real roots, will consequently be universally stable, provided there is a unique solution at all and provided

45 further that there is no inherent instability in the circuit aside from the nature of the matrix equation.

It is, therefore, a further object of this invention to provide a method of and means for electronically solving a non-singular system of simultaneous equations. It is a further object of this invention to provide a method of and means for electronically solving a non-singular system of simultaneous equations independently of the nature of the characteristic roots of the system.

A further object of this invention is to provide an improved electronic simultaneous equation solver.

A still further object of this invention is to provide an electronic simultaneous equation solver having universal stability.

A still further object is to provide an improved method of determining electronically the unknown terms of a system of non-singular simultaneous equations.

A still further object is to overcome the disadvantages and limitations of previously known systems for electronically solving a non-singular system of simultaneous equations.

The novel features that are considered characteristic of this invention are set forth with particularity in the appended claims. The invention itself, however, both as to its organization and method of operation, as well as additional objects and advantages thereof, will best be understood from the following description when read in connection with the accompanying drawings, in which

Figure 1 is a block diagram of an electronic equation solver in accordance with this invention;

Figure 2 is the circuit diagram of the networks used in Fig. 1, and

Figure 3 is a block diagram of an equation solver of the earlier type to illustrate how it may be used in practicing this invention.

Referring to Fig. 1, a signal generator 1 provides at terminals 3 and 5 a pair of voltages which are equal in amplitude and of opposite phase measured with respect to ground. This may be a D. C. generator, but because of convenience in amplifying it is preferable to use an alternating voltage having any suitable frequency, say 1000 cycles, for example. A connection bus 7, 7a distributes the voltage to each polarity reversing and potentiometer device 9, it being understood that there will be as many of these devices as there are equations to be solved.

For convenience the polarity reversing and potentiometer device is herein called a "network." Its function is to make available at its output terminal by means of a suitable switch a voltage of one phase or the other as desired, having an amplitude which is a desired known fraction of the amplitude of the voltage applied to its input. Since all networks 9 are identical the detailed construction has been shown but once in Fig. 2, to which reference is now made.

Each network includes a double-pole double-throw switch 11, an accurately calibrated potentiometer 13 having an overall resistance of, say, 1000 ohms, and a fixed resistor 15 of equal resistance. The potentiometer 13 and resistor 15 are connected between the two movable switch arms and ground while the switch contacts are connected oppositely to the bus conductors 7, 7a so that in one position of the switch the potentiometer is connected between conductor 7 and ground while the resistor is connected between conductor 7a and ground, and the connections are reversed in the other position of the switch.

Since the accuracy of the system depends to a large degree upon the accuracy with which the potentiometers can be set, they are preferably of the type consisting of a 10-turn helical resistance and are equipped with a counter and a vernier dial which enables the voltage division to be set accurately to 3 significant figures. The fixed resistor is used to load the conductor which is not in use equally with the one which is in use to pre-

vent the operation of the switch from changing the voltage by reason of a change in load impedance.

Returning again to Fig. 1, it should be noted that the networks so far described are used to establish voltages representing the constant terms $Y_1, Y_2, \dots, Y_n$ of the equations. To correlate the apparatus with the equations each component is identified by the symbol of the term which it represents, as is the voltage produced thereby. Thus the Y_1 network is set by means of the phasing switch and potentiometer so that the output voltage Y_1 produced thereby is proportionately related to the input voltage as determined by the constant term Y_1 of the equation. Of course, if the input voltage is equal to a power of 10 then the output voltage Y_1 may readily be made equal to the constant term. However, this is not necessary as will be discussed later.

The output voltages of the networks are applied through resistors 17, 17₂, ..., 17_n to the respective input terminals of a like number of identical input amplifiers 19₁, 19₂, ..., 19_n, identified as amplifiers $X'_1, X'_2, \dots, X'_n$ and each having a gain μ . The input amplifiers have push-pull output terminals to which are connected conductors 21₁, 21₂, ..., 21_n, each pair being connected to the input of n networks 9. For convenience again, these networks are identified by the coefficient term which they represent but these networks are all "primed" since the rows and columns are transposed with respect to the convention of notation adopted above. Thus amplifier X'_1 supplies the voltage $\pm X'_1$ to networks $a_{11}, a_{12}, \dots, a_{1n}$, the first subscript indicating that these networks modify the output voltage X'_1 . Similarly with the other networks.

Additional output amplifiers 23₁, 23₂, ..., 23_n are provided, the output voltages of these amplifiers representing the unknown terms of the n equations. The amplifiers are similarly identified as $X_1, X_2, \dots, X_n$ and having a gain of μ . Each output amplifier is coupled to one network of each input amplifier. Specifically, the output terminals of the "primed" or transposed networks are connected, through resistors in each case, to the input of the amplifier identified by the second number of the network subscript. Thus networks $a_{11}, a_{12}, \dots, a_{1n}$ connect, through resistors 25, 27 and 29 respectively, to the input of amplifier X_1 ; networks $a_{12}, a_{22}, \dots, a_{2n}$ connect, through resistors 31, 33 and 35, respectively, to the input of amplifier X_2 ; and networks $a_{1n}, a_{2n}, \dots, a_{nn}$ connect, through resistors 37, 39 and 41 respectively, to the input of amplifier X_n .

Each output amplifier $X_1, X_2, \dots, X_n$ is connected through one of the bus connectors 43₁, 43₂, ..., 43_n respectively, to the input of n networks 9, identified by the coefficient terms which they represent, or, otherwise stated, which produce voltages representative of the coefficients of X of the n equations. Thus output amplifier X_1 feeds into networks $a_{11}, a_{12}, \dots, a_{1n}$; amplifier X_2 feeds into networks $a_{12}, a_{22}, \dots, a_{2n}$; and amplifier X_n feeds into networks $a_{1n}, a_{2n}, \dots, a_{nn}$.

The last group of networks feeds into the first or primed set of amplifiers. In this case, however, the connections are reversed from those used to connect the first networks. Thus the networks of the second group are connected, through resistors in each case, to the input of the input or primed amplifier identified by the first number of the network subscript. Thus, network a_{11}, a_{12} and a_{1n} connect, through resistors 45, 47 and 49 respectively, to the input of amplifier X'_1 ; net-

works a_{21} , a_{22} , and a_{23} connect, through resistor 51, 53, and 55 respectively, to the input of amplifier X_2' ; and networks a_{n1} , a_{n2} and a_{nn} connect, through resistors 57, 59 and 61, respectively, to the input of amplifier X_n' .

Let X_1 , X_2 . . . X_n be the output voltages measured to ground across the output of amplifiers bearing the same identification (+ and - values are available); let E_1 , E_2 . . . E_n be the residual voltages at the input terminals of amplifiers X_1' , X_2' . . . X_n' ; and let E_1' , E_2' . . . E_n' be the residual voltages at the input terminals of amplifiers X_1 , X_2 . . . X_n , then we can write:

$$E_1' = \frac{1}{n} [a_{11}' \mu' E_1 + a_{21}' \mu' E_2 + \dots + a_{n1}' \mu' E_n] \quad (7)$$

$$E_2' = \frac{1}{n} [a_{12}' \mu' E_1 + a_{22}' \mu' E_2 + \dots + a_{n2}' \mu' E_n] \quad (8)$$

$$E_n' = \frac{1}{n} [a_{1n}' \mu' E_1 + a_{2n}' \mu' E_2 + \dots + a_{nn}' \mu' E_n] \quad (9)$$

and

$$X_1 = \mu E_1' \text{ or } E_1' = \frac{X_1}{\mu} \quad (10)$$

$$X_2 = \mu E_2' \text{ or } E_2' = \frac{X_2}{\mu} \quad (11)$$

$$X_n = \mu E_n' \text{ or } E_n' = \frac{X_n}{\mu} \quad (12)$$

Similarly,

$$E_1 = \frac{1}{n+1} [a_{11} X_1 + a_{12} X_2 + \dots + a_{1n} X_n + Y_1] \quad (13)$$

$$E_2 = \frac{1}{n+1} [a_{21} X_1 + a_{22} X_2 + \dots + a_{2n} X_n + Y_2] \quad (14)$$

$$E_n = \frac{1}{n+1} [a_{n1} X_1 + a_{n2} X_2 + \dots + a_{nn} X_n + Y_n] \quad (15)$$

substituting (10), (11) and (12) in (7), (8) and (9) factoring μ' ; and rearranging

$$\frac{nX_1}{\mu' \mu} = a_{11}' E_1 + a_{21}' E_2 + \dots + a_{n1}' E_n \quad (16)$$

$$\frac{nX_2}{\mu' \mu} = a_{12}' E_1 + a_{22}' E_2 + \dots + a_{n2}' E_n \quad (17)$$

$$\frac{nX_n}{\mu' \mu} = [a_{1n}' E_1 + a_{2n}' E_2 + \dots + a_{nn}' E_n] \quad (18)$$

By design the product $\mu' \mu$ is made very large, say of the order of ten to fifteen thousand, so that the terms

$$\frac{nX_n}{\mu' \mu}$$

can be considered as being substantially zero and the right hand portion of each equation (16), (17) and (18) is then equal to zero.

In the matrix notation, the n equations (7) to (9) may be written:

$$E' = \frac{1}{n} \mu' A'^{tr} E \quad (19)$$

from (10) to (12) we obtain

$$X = \mu E' \quad (20)$$

equations (13) to (15) may be written

$$E = \frac{1}{n+1} [AX + Y] \quad (21)$$

and from (16) to (18)

$$\frac{nX}{\mu' \mu} = A'^{tr} E \quad (22)$$

Finally, substituting (21) in (22)

$$\frac{(n+1)n}{\mu' \mu} X = A'^{tr} [AX + Y] \quad (23)$$

$$\therefore \text{Thus, if } \frac{(n+1)n}{\mu' \mu} \text{ is small, } A'^{tr} [AX + Y] = 0 \quad (24)$$

Now, if A' is itself non-singular it must be true that

$$AX + Y = 0 \quad (25)$$

Hence X is the required solution.

For the stability analysis, consider Equation 23. This is analogous to the equation developed in the Brown-Goldberg patent application referred to above, in which $A'^{tr} A$ replaces A , $A'^{tr} Y$ replaces Y and

$$\frac{\mu \mu'}{n(n+1)} \text{ replaces } \frac{\mu}{n+1}$$

Thus, for purposes of stability the characteristic roots of $A'^{tr} A$ are relevant now, instead of the roots A . The necessary and sufficient condition for stability is that each hypothetical single loop corresponding to a gain characteristic

$$\frac{\mu \mu'}{n(n+1)}$$

and feedback network λ where λ is a characteristic root of A , be stable in itself.

Now, if A' is chosen so that $A' = A$, i. e., $a_{ij}' = a_{ij}$, for all i, j , then the relevant matrix is $A'^{tr} A$. As stated above, the characteristic roots of $A'^{tr} A$ are all positive, if A is non-singular. Then the system can be universally stable, for all non-singular matrices A , if a_{ij}' is chosen equal to a_{ij} , and if

$$\frac{\mu \mu'}{n(n+1)}$$

represents a stable feedback amplifier characteristic.

To use the equation solver set the various controls at the values determined by the terms which they represent, it being noted that for each a' network there is an "a" network having an identical setting. It follows therefore that the apparatus may be simplified by physically ganging the corresponding "a" and "a'" networks. This greatly reduces the number of dials that need be set to solve a given equation.

The actual value of the unknown terms may be determined in one of two ways:

(a) Adjust the output of generator 1 to a value equal to a power of ten, positive or negative, which is large enough to include the values of the constant terms of the equations to be solved. The coefficient-representing voltages may then be made exactly equal to the coefficients themselves by adjusting the calibrated dials, and the unknown terms are then determined by reading the voltage output of the X amplifiers with a suitable voltmeter, and the polarity determined by comparing the phase, in each case, with a reference phase.

(b) Adjust the output of generator 1 to any convenient value and compare the X voltages, in turn, to the generator output to determine what fraction of the reference generator voltage the unknown voltage is. This may be accomplished, for example, by means of a bridge circuit which is fully described in the copending application of Brown and Goldberg referred to above. In this case no errors are introduced by errors in the voltmeter or changes in the amplitude of the reference voltage which may occur after it has once been set to the desired value,

This system greatly simplifies the use of the apparatus, and is preferred, since it eliminates the necessity of constantly checking the input voltage and the voltmeter.

In the earlier system it was pointed out that the ability to make a determination is dependent upon the system itself being stable, and this required the design of a special amplifier which had a phase tolerance not exceeding 90° throughout the range of frequencies for which the effective amplifier gain

$$\frac{\mu}{(n+1)}$$

exceeded unity, but at the same time the amplifier gain was required to be very large, a factor normally contributing to instability. With a 1000 cycle gain of about 15,000, in the earlier case, band pass filters were used to attenuate the gain at frequencies above and below 1000 cycles, but to insure the necessary phase tolerance it was necessary to consider the operation of the amplifier between very wide frequency limits extending from a fraction of a cycle to nearly 10,000 k. c. Moreover, stability was ensured only for matrices whose characteristic roots have positive real parts. In the present case the effective gain

$$\frac{\mu\mu'}{n(n+1)}$$

is the product of the gain of two amplifiers. Consequently each amplifier may have a much smaller net gain at 1000 cycles than was previously required. Thus if $\mu' = \mu$, the gain of each amplifier need now be equal to the square root of that previously required. In the present case the effective gain of each amplifier may be of the order of 100 to 125, say, a condition much easier to fulfill.

The phase tolerance condition in the present case is $\pm 180^\circ$. This may be divided equal $\pm 90^\circ$ for each amplifier, or one may compensate for excessive phase shift of the other. However, since the gain is so low, no difficulty is encountered in meeting this requirement. The low gain, of course, greatly reduces the frequency range over which it is necessary to consider the phase shift, although as before it must be kept within the limit stated above for all frequencies for which the effective gain exceeds unity. As a practical matter, conventional amplifiers can be used without difficulty since such amplifiers normally meet the phase tolerance limitation.

It should be understood, however, that μ' need not be equal to μ . In fact either one of the amplifiers may have unity gain. As a practical matter this is not preferred, however, because the high gain of the other amplifier then increases the difficulty of phase control and no advantage is realized over the earlier system with regard to amplifier design.

A further interesting feature of the present invention is that the accuracy of solution is substantially independent of the actual settings of the a' networks. This can be demonstrated by setting up a system of equations, obtaining the solution, and then varying the a' potentiometer settings over wide ranges. By observation it can be seen that the indicated solution does not change. The only effect of an extreme variation of these potentiometers is ultimately to destroy stability as evidenced by internal oscillations being established. This means that the only contribution of the a' networks is to insure stability, which fact substantiates the theory above, since

the transposed matrix network was introduced only for the purpose of insuring universal stability. As a practical matter the advantage of this fact is that the a' potentiometers need not be accurate, but may be inexpensive small potentiometers ganged to the respective accurately calibrated potentiometers of the "a" group. Aside from the use of additional amplifiers, the cost and size of the improved equipment is increased but slightly.

This result may be confirmed by an analysis of Equations 13 to 18 based on the fact that when

$$\frac{nX_1}{\mu'\mu}$$

is small, as it is, Equations 16 to 18 are substantially equal to zero. Use is made of a mathematical theorem that when A^{tr} is non-singular the solution is independent of the values of a' , which is well known and need not be explained herein.

Various modifications may be made in the apparatus described herein to illustrate the present invention. In Fig. 2, for example, the resistor 15 and the potentiometer 13 may conveniently be connected in the plate and cathode circuits of an amplifier tube, thus eliminating the need of a coupling transformer. In fact such is the preferred method of obtaining the reference voltage which is described fully in the copending Brown and Goldberg application. In such case the resistor and potentiometer will not return to ground directly but to suitable sources of plate voltage and cathode bias, switching of these connections being accomplished by additional contact arms on the polarity reversing switch 11.

The apparatus described in the earlier Brown and Goldberg application may also be used in practicing the present invention. This is explained in connection with Fig. 3 which is a simplified block diagram of the earlier device and to which reference is now made. The left hand column of networks 9 are the four Y networks of a device presumed to have been constructed in accordance with the earlier type of equation solver and having sufficient places to solve four simultaneous equations in four unknowns. Such a device includes sixteen additional "a" networks arranged in four rows and four columns, and interconnected as shown. The dashed lines indicate that for the present use of the equipment the networks are to be grouped in four groups, each containing four networks. It will be understood that the interconnections of these networks and the four associated X amplifiers are as described in the earlier application. No transposed "a" networks are included in the original connection.

This arrangement can be used in accordance with the present invention to solve two simultaneous equations in two unknowns with universal stability provided the gain of each amplifier is reduced sufficiently to prevent oscillation, say by a factor of 10:1. To solve the equations the potentiometers of the upper two Y networks and the 4 potentiometers of the group 65 are all set at 0 as indicated by the "0" in each rectangle. The networks of group 67 in the upper right hand corner are set in accordance with the "a" coefficients of X, the first row representing the coefficients of X_1 and the second row representing the coefficients of X_2 . The two lower Y networks are set to represent the Y terms of the two equations, as shown. The group of 4 networks 71 in the lower left-hand corner are set to represent the

same "a" coefficients put in transposed order and reversed in sign. Thus the coefficients of X_1 are set in the first column and the coefficients of X_2 in the second column, as shown. The networks of group 69 are all set to zero.

The identity of the circuits of Figs. 3 and 1 may be observed. The input which is proportional to Y is applied to the respective amplifiers now identified as X_1' and X_2' , and which correspond to amplifiers 19₁ and 19₂ of Fig. 1. Connected to these amplifiers are the networks 71 representing the A^{tr} matrix. Thus, networks a_{11}' and a_{21}' feed into amplifier X_1 while a_{12}' and a_{22}' feed into amplifier X_2 . The amplifiers X_1 and X_2 feed the A matrix networks in which a_{11} and a_{12} feed back into amplifier X_1' , while networks a_{21} and a_{22} feed back into amplifier X_2' . The other networks are not operative since no voltage is developed by the network when it is set at 0.

It was previously stated that μ'/μ must be large, say of the order of 10 to 15 thousand. Because the method of using the original equipment to provide universal stability effectively connects the amplifiers in series, the resultant gain would be of the order of 10,000² unless the individual gain is reduced. This should be done as stated above. However, an alternative method is to use the networks of groups 65 or 69 to pass a feedback voltage to either the X or X' amplifiers in the proper phase to thereby produce 100% degeneration, or unity gain. For example, set the diagonal networks 73 and 75 of group 69 at maximum output and negative phase. It may be observed that this simply applies to each X amplifier the full amplifier voltage in phase required to degenerate the gain. Alternatively the X amplifier could be degenerated in the same manner.

There has thus been described a new method of electronically solving a plurality of simultaneous equations wherein universal stability is attained by producing voltages which represent the terms of the equations and modifying the voltages in a manner analogous to the mathematical procedure of operating on the unknown X with a coefficient matrix and then a transposed coefficient matrix to produce voltages representative of the unknown values. Further, apparatus has been described which may be used to practice this invention together with several modifications thereof.

What I claim is:

1. The method of determining the unknown terms of a plurality of simultaneous equations which includes the steps of providing a plurality of input voltages representative of the values of the constant terms of each equation respectively; amplifying said voltages by a factor μ' , deriving from each of said amplified voltages a plurality of voltages approximately representative of the values of the coefficients of the respective unknowns; combining a voltage from each of said plurality of voltages with the voltage of every other plurality of voltages representative of the coefficient of the same unknown; amplifying said combined voltages by a factor μ to produce output voltages indicative of the values of the unknown terms of said equations, respectively; deriving from each of said output voltages a plurality of feedback voltages representative of the coefficients of a given unknown; and combining with each input voltage the ones of said feedback voltages which represent the coefficients of the unknown terms of the equation associated with each constant term.

2. The method set forth in claim 1 which in-

cludes the additional step of maintaining the overall amplification measured by the product of μ and μ' at a high value compared to the absolute values of the other terms of the equations to be solved.

3. The method of solving n simultaneous equations of n unknown terms of the type

$$Y_1 = a_{11} X_1 + a_{12} X_2 + \dots + a_{1n} X_n$$

$$Y_2 = a_{21} X_1 + a_{22} X_2 + \dots + a_{2n} X_n$$

$$\vdots$$

$$Y_n = a_{n1} X_1 + a_{n2} X_2 + \dots + a_{nn} X_n$$

when Y is a constant, X an unknown and a the coefficient of X , which includes the steps of providing n input voltages representative of the n values of Y ; amplifying said voltages by a factor μ' to produce n first resultant voltages; deriving from each of said first resultant voltages n coefficient-representing voltages representative of the coefficients of X of a given equation; combining the coefficient-representing voltages representing the coefficients of the same unknown terms to produce n second resultant voltages; separately amplifying said second resultant voltages by a factor μ to produce n output voltages indicative of the values of the unknown terms of said equations; deriving from each of said output voltages n feedback voltages representative of the coefficients of a given unknown term; and combining with said input voltages the ones of said feedback voltages which represent the coefficients of the unknown terms of the equation associated with each constant term.

4. The method of solving electronically a plurality of simultaneous equations which includes the steps of providing a first group of voltages whose amplitudes and phases are to determine the sign and value of the unknown terms of the equations, respectively, deriving a second group of voltages corresponding to the operation of a coefficient matrix A on each unknown term, combining said second group of voltages with additional voltages representing, respectively, the constant terms of said equations, amplifying said combined voltages to produce a third group of voltages, operating on said third group of voltages with a coefficient matrix A^{tr} to produce a fourth group of voltages, and amplifying said fourth group of voltages, the latter amplified voltages constituting the first group of voltages, and measuring said last named voltages to determine the values of the unknown terms of said equations.

5. The method of determining the values of the unknown terms of n simultaneous equations of the type,

$$Y_1 = a_{11} X_1 + a_{12} X_2 + \dots + a_{1n} X_n$$

$$Y_2 = a_{21} X_1 + a_{22} X_2 + \dots + a_{2n} X_n$$

$$\vdots$$

$$Y_n = a_{n1} X_1 + a_{n2} X_2 + \dots + a_{nn} X_n$$

where Y is a constant, a is a coefficient of X and X an unknown, which includes the steps of providing n input voltages representative of the values of Y_1, Y_2 to Y_n ; separately amplifying said input voltages, deriving from each amplified voltage n coefficient-representing voltages whose polarities and amplitudes are determined by the coefficients of X of the respective equations; combining the coefficient-representing voltages which represent the various coefficients of the same unknown to produce n resultant voltages; separately amplifying said resultant voltages, the amplitudes and phases of said amplified resultant voltages being proportional to the values of said unknown terms X_1, X_2 and X_n respectively; deriv-

ing from each of said amplified resultant voltages n feedback voltages representative of the n coefficients of X_1 , X_2 and X_n respectively; and combining with said input voltages the ones of said feedback voltages which represent the coefficients of the unknown terms of the equation associated with each constant term.

6. A device of the character described which includes a source of voltage, a first plurality of voltage dividers connected to said source; a first group of amplifiers connected one to each voltage divider, a second plurality of voltage dividers connected to the output of each amplifier, the output of each voltage divider of a given amplifier being coupled to one voltage divider of each other amplifier and to one of a second group of amplifiers; a third plurality of voltage dividers connected to the output of each amplifier of the second group, the output of each voltage divider of a given amplifier of the second group being coupled to the output of one voltage divider of each other amplifier of the second group and to the input of one of the first group of amplifiers.

7. A device of the character described in claim 6 in which the voltage dividers of both groups are coupled together through resistors.

8. A device of the character described in claim 6 in which the product of the gain of the amplifiers of the first group multiplied by the gain of the amplifiers of the second group is of the order of ten thousand.

9. A device of the character described in claim 6 in which there is associated with each voltage divider means for reversing the phase of the output voltage produced thereby.

10. An electronic simultaneous equation solver comprising a source of voltage; a plurality of networks connected to said source, a like number of input amplifiers, the output of each network being resistance coupled to the input of one of said amplifiers; a second group of networks, a plurality of said networks being connected to the output of each input amplifier; a like number of output amplifiers, the input of each output amplifier being coupled by a resistance to one of the networks of each input amplifier; and a third group of networks connected to the output of each output amplifier, one network of each output amplifier being coupled to each of said input amplifiers.

11. An electronic simultaneous equation solver which comprises a first group of voltage dividers connected to a source of reference potential and adapted to be set to represent the constant terms of a system of non-singular simultaneous equations, a second group of voltage dividers adapted to be set to represent the coefficients of the unknown terms of the system of equations, a third group of voltage dividers individually coupled to respective ones of said second group of voltage

60

dividers; and means including amplifiers interconnecting said networks whereby output voltages are obtained which are proportional to the unknown terms of said system of equations independently of the nature of its characteristic roots.

12. A device of the character described in claim 10 in which each network of said third group is mechanically coupled to and adjustable with one network of said second group.

13. A device for electronically determining the values of the unknown terms of a system of n simultaneous equations of the type

$$Y_1 = a_{11} X_1 + a_{12} X_2 + \dots + a_{1n} X_n$$

$$Y_2 = a_{21} X_1 + a_{22} X_2 + \dots + a_{2n} X_n$$

$$\vdots \quad \vdots \quad \vdots \quad \vdots \quad \vdots \quad \vdots$$

$$Y_n = a_{n1} X_1 + a_{n2} X_2 + \dots + a_{nn} X_n$$

where Y_1 , Y_2 . . . Y_n are constant terms, X_1 , X_2 . . . X_n the unknown terms and a the coefficients of the unknown terms which are identified by the second subscript in the equations which are identified by the first subscript, which includes means for producing input voltages representative of the constant terms Y_1 , Y_2 . . . Y_n ;

an input amplifier for separately amplifying each of said voltages; a first plurality of voltage dividing networks connected to each input amplifier, said networks being adapted to be set at least approximately to the fractional values of the amplified voltages Y_1 , Y_2 . . . Y_n which are determined by the values of the "a" coefficients whose first subscripts are 1, 2, . . . n , respectively; means for combining the voltages representing the "a" coefficients whose second subscripts are 1, 2, . . . n , respectively to produce n resultant voltages; an output amplifier for separately amplifying each of said resultant voltages; a second plurality of voltage dividing networks connected to each output amplifier, the latter network being adapted to be set to the fractional values of the amplified voltages Y_1 , Y_2 . . . Y_n which are determined by the values of the "a" coefficients whose second subscripts are 1, 2, . . . n , respectively; means for combining the voltages developed representing the "a" coefficients whose first subscripts are 1, 2, . . . n , respectively, to produce n feedback voltages; and means for combining said feedback voltages with respective ones of said input voltages; the amplitudes of the amplified resultant voltages being indicative of the value of said unknown terms.

14. A device of the character described in claim 13 in which the networks of said first plurality are ganged with the networks of the second plurality which are to be set to represent coefficient voltages identified by the same subscripts.
